UNITED STATES PATENT OFFICE.

ANTHONY J. PRENOSIL, OF DWIGHT, NEBRASKA, ASSIGNOR OF ONE-HALF TO FRANK J. MAIXNER, OF DWIGHT, NEBRASKA.

CONTAINER FOR MUCILAGE.

1,227,658.

Specification of Letters Patent.

Patented May 29, 1917.

Application filed October 7, 1916. Serial No. 124,387.

To all whom it may concern:

Be it known that I, ANTHONY J. PRENOSIL, a citizen of the United States, residing at Dwight, in the county of Butler and State of Nebraska, have invented certain new and useful Improvements in Containers for Mucilage, of which the following is a specification.

This invention relates to containers, and 10 more particularly to a container for mucilage and the like.

One of the main objects of the invention is to provide a device of the character stated so constructed as to prevent gumming 15 of the mouth of the container such as occurs in the ordinary glue or mucilage bottle.

A further object is to provide a container having a closure member so constructed and mounted as to act as a supplemental container 20 when in operative position.

Further objects will appear from the detailed description.

In the drawings:

Figure 1 is a top plan view of the container with the closure member in open position.

Fig. 2 is a section on line 2—2 of Fig. 1.

Fig. 3 is a view similar to Fig. 2 showing the position of the cover and U-strip when 30 cover is in closed position.

The body 1 of the container is of approximately rectangular horizontal cross section and of irregular polygonal vertical cross section. The under front wall of this 35 member is inclined downward and inward at an angle, as at 1^a. The bottom 2 is made much thicker than the rest of the body of the container so as to provide sufficient weight to maintain the container in upright 40 position and avoid tilting of the same.

The container is provided with an integral upwardly extending neck 3. A U strip 4 of metal is secured about the upper end of this neck. A cover or closure member 8 is secured to the back bar of the U strip by means of an integral downwardly extending tongue 7 soldered or secured in any other suitable manner to the inner face 45 of back bar 3^a. This cover is of rectangular shape underneath and is concave in transverse cross section. The cover 8 is formed of sheet metal and is of such size as to fit snugly over the neck 3, for which purpose it is provided with an integral base, 50 flange 8^a. When in open position the under

or inner face of the cover forms a continuation of the inclined front wall 1^a of the container, and is flush, at its lower edge, with the inner face of back bar 3^a of U strip 4. In this position the concave cover is well 60 adapted to receive and temporarily retain mucilage which is caused to flow from the container by tilting the same forward and downward. When the container is thus tilted the mucilage will flow into the concave cover 8 and will be retained thereby, 65 the cover thus constituting a temporary supplemental container. The mucilage which is held by the cover is readily accessible thus eliminating the necessity of passing 70 a brush into and out of the container neck as is done in containers of the ordinary construction, thus eliminating the chief source of mucilage becoming spilled or smeared about the mouth of the container and causing 75 a collection of hardened mucilage about the same, commonly termed "gumming". After the desired amount of mucilage has been used the container is returned to its initial position. This causes the mucilage 80 contained by the cover to flow back into the container, after which the U strip 4 may be removed from neck 3 and the member 8 placed about the neck so as to tightly 85 close the same. The U-strip 4 and cover 8 are so relatively disposed that, when the cover is placed over the neck the strip is parallel with, and closely adjacent to, the under face of the inclined front wall 1^a. In this position the strip has no tendency to 90 loosen the cover or cause its removal from the neck 3.

What I claim is:

1. In containers, a body having an upwardly and outwardly inclined neck and front wall, and a concaved supplemental container mounted at the upper edge of the front wall of the body and forming a continuation thereof whereby, when the body is tilted inward the contents thereof will 95 flow into said supplemental container, and when the body is returned to its normal position the contents of said supplemental container will drain back into the said body.

2. In containers, a body having an upwardly and outwardly inclined neck and front wall, a concaved supplemental container mounted at the upper edge of said front wall and forming approximately a continuation thereof, said supplemental 105 110

container being adapted to fit snugly about the neck and front wall of the body, and means for detachably securing the supplemental container in operative position adjacent the upper edge of the front wall of said body.

3. In a container of the character described, the combination of a body having an outwardly inclined neck and a similarly inclined front wall, a U strip secured about the upper edges of the said neck and the

inclined front wall of the body, and a concave closure member secured at its lower edge to the said U strip, said cover member being adapted to fit snugly about the said neck so as to effect a tight closure therewith. 15

In testimony whereof I affix my signature in presence of two witnesses.

ANTHONY J. PRENOSIL.
